Inventor,
Ellsworth B. Riley
by Augustus R. Lopps,
his Attorney.

UNITED STATES PATENT OFFICE.

ELLSWORTH B. RILEY, OF PHILADELPHIA, PENNSYLVANIA.

SPARK PLUG.

Application filed June 9, 1922. Serial No. 587,142.

To all whom it may concern:

Be it known that I, ELLSWORTH B. RILEY, a citizen of the United States, residing in Philadelphia, Pennsylvania, have invented 5 certain new and useful Improvements in Spark Plugs, of which the following is a specification.

One object of my invention is to provide an improved spark plug which can be used 10 in connection with internal combustion engines and to so construct said plug that parts thereof will prevent oil, soot and carbon from entering the chamber of the outer electrode and collecting on the inner wall there- 15 of; the construction also being such as to prevent said collection or deposit of oil, soot and carbon on the outer walls of the central electrode and its insulator.

Another object of my improved construc- 20 tion is to prevent the flame of the explosion from coming in contact with the central electrode insulator, thereby avoiding crack- ing or injury to the insulator.

A further object is to provide adequate 25 means which will shield the sparking surface of the outer electrode; said means being preferably in the form of an upwardly flar- ing annular skirt which will receive any surplus oil that might run down from the 30 outer surface of the plug.

Another object of my invention is to pro- 35 vide the lower sparking surface of the outer electrode with an annular portion flaring upward in cross section to correspond with the central electrode; the latter having a 40 projection forming an annular raised spark crest insuring an adequate spark around the complete circle of the sparking gap.

Furthermore, I preferably make the lower 45 portion of the central electrode cone shape and of such size as to include a portion which extends outward beyond the sparking surface so as to prevent oil and other sub- stances from being pumped to the interior 50 of the plug during the operation of the engine.

These objects, and other advantageous 55 ends which will be described hereinafter, I attain in the following manner, reference 60 being had to the accompanying drawings in which—

Figure 1 is an elevational view of a spark plug made in accordance with my invention,

Figure 2 is a central longitudinal section

of said plug, the central electrode being 55 illustrated in outside elevation,

Figure 3 is an enlarged transverse section, taken on the line 3—3 of Figure 1,

Figure 4 is an enlarged transverse section taken on the line 4—4 of Figure 1, and 60

Figure 5 is a greatly enlarged fragmentary sectional view of the lower portion of said plug.

Referring to the drawing, 6 represents an outer electrode made in the form of a hollow 65 metallic body portion. This body portion has an externally screw threaded part 7 adapted to be screwed in a tapped opening in an internal combustion engine in the usual manner of attaching spark plugs. 70

The body portion 6 includes a hollow downward extending skirt 8 which depends from the portion 7. The outer downwardly tapering surface 9 of the skirt 8 adjacent its bottom intercepts an annularly extending 75 upper ledge surface or shoulder 10; said ledge surface being produced by a peripheric flange 11 of the skirt 8.

The ledge surface 10 preferably flares up- 80 ward at a slight angle to the horizontal for a purpose hereinafter rendered obvious. The outer surface 12 of the flange 11 tapers downwardly from the outer edge 13 and terminates in an annular lower edge 14.

From the edge 14 the inner surface por- 85 tion 15 of the flange 11 tapers upwardly and preferably intercepts an upwardly tapering annular surface portion 16 of the flange 11; said surface portion 16 prefer- ably extending at a steeper angle to the hori- 90 zontal than does the surface portion 15.

A central electrode 17 includes a rod 18 which extends through the body portion 6 and through an insulator 19. In the form illustrated the insulator has an enlargement 95 20 which is held against a sledge 21 of the body portion by a gland nut 22 which is screwed into the top of the body portion 6. Also in the form illustrated the rod 18 of the central electrode has an integral collar or 100 enlargement 23 which abuts a lower shoulder 24 of the insulator 19. The upper end of the rod 18 is screw threaded and, at a position above the top end of the insulator, a nut 25 engages the screw threaded portion 105 of the rod 18 and serves to secure the central electrode 17 to the insulator.

A wire-binding nut 26 is mounted on the

top of the rod 18 for the purpose of securing an electric conduit wire in connection with the central electrode; the outer electrode being electrically grounded on the 5 engine in the usual manner.

The lower end of the electrode rod has thereon a metallic terminal cap which flares upwardly, preferably from the bottom of the rod 18 to an annular edge 28, said edge 10 being of greater diameter than the edge 14 of the flange 11. The terminal cap 27 has an annular top surface portion 29 which extends inwardly from the edge 28 to an annular 15 sparking crest flange 30.

18 This sparking crest flange 30 extends above the level of the surface portion 29 and terminates in the annular edge 31 below the surface portion 16, said edge 31, in the form illustrated, being of smaller diameter 20 than the edge 14 of the flange 11.

15 The crest flange 30 has an outer surface portion 32 which flares downward from the edge 31 slightly below the surface portion 25 15 of the flange 11, and this surface portion 32 preferably intercepts an annular downwardly flaring surface portion 33 of the crest flange 30. The surface portion 33 intercepts the surface 29, the lower portion of the surface 33 preferably being of greater diameter 30 than the edge 14 of the flange 11.

35 The terminal cap 27 can be secured to the lower end of the rod 18 in any suitable manner, such for example as by welding, forced fit, or brazing, or if desired said cap can be made integral with the rod 18.

40 The space between the surface portions 15 and 32 forms an annular sparking gap and thus the sparks can occur throughout the entire areas of these surfaces and also 45 between the edges 14 and 31.

45 In the use of my improved plug, any oil or products of combustion which strike the surface 9 of the skirt 11 will run down over said surface and collect on the ledge surface 10.

50 If said oil or products of combustion should be in such quantity as to run over the edge 13 they will immediately shed downward onto the outer slanting surface of the crest flange 30 and surface 29 of the cap 27. Therefore the arrangement of parts is such that said oil and products of combustion will 55 not engage the surface 32 or edge 31.

55 The cap 27, by being made frusto-conical and of the relative proportions with respect to the flange 11 above set forth, will serve to prevent the flame of the combustion or the products of combustion from entering the lower opening of the skirt 8, since the edge 28 is of such diameter as to serve as a guard to prevent the flame and products of combustion from directly passing through the opening of the body portion into the chamber thereof.

60 Furthermore, the electrode insulator will

be protected against the direct fire of the combustion and thus the possibilities of injury to the insulator are reduced to a minimum.

65 By the construction of parts as above set forth and as illustrated I have found in actual practice and use of the device that the sparking portions are kept practically free of any carbon or other deposit as are also the other portions contained within the 75 body electrode.

70 While I have described my invention as taking a particular form, it will be understood that the various parts of my invention may be changed without departing from the 80 spirit thereof, and hence I do not limit myself to the precise construction set forth, but consider that I am at liberty to make such changes and alterations as fairly come 85 within the scope of the appended claims.

Having thus described my invention, what I claim as new and desire to secure by Letters Patent is:—

1. A spark plug including a depending electrode body providing an opening at its 90 lower end; and an electrode having a cap provided with a sparking crest below said end of the body, said crest in cross section having its outer side slanting outwardly and downwardly, said outer side of the crest 95 having its upper portion extending to a position closer to the longitudinal axis of the plug than is the lowest part of the wall of said opening whereby oil running down from said wall will drop onto said outer side 100 of the crest.

2. A spark plug having an electrode body, the lower part of said body having a downwardly slanting lower surface terminating in a lower edge; and a second electrode having a sparking crest with an outwardly and downwardly slanting surface directly 105 opposed to and under said edge of the body.

3. A spark plug having an electrode body, the lower part of said body having a downwardly slanting lower surface terminating in a lower edge; and a second electrode having a sparking crest with an outwardly and downwardly slanting surface directly 110 opposed to and under said edge of the body, said body having a surrounding oil collecting pocket above said edge, said body having a surface leading from the overflow part of said pocket to said edge whereby any overflow oil running down said 115 latter surface will fall on the outer side of said crest.

4. A spark plug having a depending electrode body with a part providing a lower opening; and a second electrode having a portion extending through said opening and another portion spaced below said opening of greater diameter than said part of the electrode body, said second mentioned portion of said second electrode having a sparking 125 130

crest flange below said opening, said crest flange having a portion of smaller diameter than the lower part of said opening.

5. A spark plug having a depending electrode body with a part providing a lower opening; and a second electrode having a portion extending through said opening and another portion spaced below said opening of greater diameter than said part of the

10 electrode body, said second mentioned portion of said second electrode having a sparking crest flange below said opening, said crest flange having a portion of smaller diameter than the lower part of said opening,

15 said second mentioned portion of the second electrode also having an upper surface portion projecting outside the confines of said sparking crest.

6. A spark plug having a depending electrode body portion including a lower edge providing an opening; and a second electrode having a portion in alignment with said opening including a flange providing a sparking crest, said sparking crest flange 25 including a portion below said opening of smaller diameter than said lower edge of the body electrode.

7. A spark plug having a depending electrode body portion including a lower edge

providing an opening; and a second electrode having a portion in alignment with said opening including a flange providing a sparking crest, said sparking crest flange including a portion below said opening of smaller diameter than said lower edge of the body electrode, said sparking crest flange having an outer portion of greater diameter than said edge of the body electrode.

8. A spark plug including a depending electrode body providing an opening; and a central electrode having a cap below said opening provided with a sparking crest, said cap having a portion extending beyond said crest.

9. A spark plug including a depending electrode body having a sparking flange which in cross section tapers downwardly; and a central electrode having a cap with a sparking crest flange below said first flange, said crest flaring downwardly in 50 cross section.

In testimony whereof, I have signed my name to this specification, in the presence of two subscribing witnesses.

ELLSWORTH B. RILEY.
